UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

ROTATION DEVICE FOR DRILLS.

1,009,301.

Specification of Letters Patent. Patented Nov. 21, 1911.

Application filed December 18, 1908. Serial No. 468,150.

To all whom it may concern:

Be it known that I, CHARLES C. HANSEN, a citizen of the United States, and resident of Easton, in the county of Northampton 5 and State of Pennsylvania, have invented a new and useful Rotation Device for Drills, of which the following is a specification.

This invention relates to rotation devices for drills and has for its object to provide a 10 novel rotation device arranged to impart an intermittent movement in one direction to the drill steel and hold it against rotary movement in the opposite direction, the said rotation device including an oscillating 15 member arranged to be clutched to and released from the drill steel, and a pair of fluid pressure controlled pistons for oscillating said member.

A practical embodiment of my invention 20 is represented in the accompanying drawings, in which the invention is shown in connection with a hammer drill.

Figure 1 represents in longitudinal central section so much of a hammer drill as 25 will give a clear understanding of the construction, location and operation of my improved rotation device, Fig. 2 is a transverse section taken in the plane of the line A—A of Fig. 1, looking in the direction of the 30 arrows, and Fig. 3 is a transverse section taken in the plane of the line B—B of Fig. 1, looking in the direction of the arrows.

The tool piston 1 is fitted to reciprocate in the cylinder 2 and is arranged to strike the anvil block 3. A chuck 4 is rotatably mounted in the front end of the cylinder 2 and is held in position by a front head 5. The angular shank of the drill steel 6 is removably inserted into the chuck 4 into position 40 to be engaged by the anvil 3. An oscillating ring 7 is mounted in the front head 5 and surrounds the chuck 4.

Any device may be employed for clutching and releasing the chuck and oscillating 45 ring, that shown herein being of the well known pawl and ratchet type, in which spring pressed pawls 8 are mounted in the oscillating ring 7 and the chuck 4 is provided with an annular series of ratchet teeth 50 9. The oscillating ring 7 is provided with diametrically opposed wings or abutments 10, 11, fitted to reciprocate in recesses 12, 13,

in the front head 5. This front head is further provided with a pair of pistons 14, 15, fitted to reciprocate in the chambers of two 55 cylinders 16, 17, on the front head 5, the rods 18, 19, of which pistons are engaged with the abutments 10, 11, of the oscillating ring 7. These oscillating ring operating pistons are reciprocated by the motive fluid 60 which operates the drill and the movements of these pistons are controlled by the hammer piston 1 as follows:—A passage 20 leads from the chamber of the cylinder 16 at the upper side of the piston 14 to the front 65 end of the hammer piston chamber and a passage 21 leads from the chamber of the cylinder 17 at the upper side of the piston 15 to the rear end of the hammer piston 70 chamber.

In operation, as the hammer piston 1 is reciprocated, it will open and close the passages 20, 21, leading to the oscillating ring operating pistons 14, 15, thus reciprocating these pistons 14, 15, and because of their engagement with the abutments 10, 11, of the oscillating ring, will operate the said ring. 75

What I claim is:—

1. In a device of the character described, a front head having two separate piston 80 chambers on the same side of the front head and two separate recesses, a drill, a member for rotating the drill having diametrically opposed abutments fitted to oscillate in said recesses and pistons fitted to reciprocate in 85 said chambers and engaged with said abutments.

2. In a device of the character described, a front head having two separate piston chambers on the same side of the front head 90 and two separate recesses, a drill, a member for rotating the drill having diametrically opposed abutments fitted to oscillate in said recesses, pistons fitted to reciprocate in said chambers and piston rods extending from 95 the piston chambers into the recesses and engaged with said abutments.

3. In a device of the character described, a main cylinder, its piston, a front head having two separate auxiliary piston chambers 100 on the same side of the front head, and two recesses, passages leading from the main piston chamber to the separate auxiliary piston chambers, a drill, a member for rotating the

drill having diametrically opposed abutments fitted to oscillate in said recesses and pistons fitted to reciprocate in said auxiliary piston chambers and engaged with said abutments.

In testimony, that I claim the foregoing as my invention, I have signed my name in

presence of two witnesses, this 15th day of December 1908.

CHARLES C. HANSEN.
